UNITED STATES PATENT OFFICE.

FREDERICK L. KINSEY, OF BUFFALO, NEW YORK, ASSIGNOR OF ONE-HALF TO JOHN D. BROTHERSTON, OF DERBY, NEW YORK.

LOCKING HAT, COAT, AND UMBRELLA RACK.

978,033.

Specification of Letters Patent.

Patented Dec. 6, 1910.

Application filed January 29, 1910. Serial No. 540,911.

To all whom it may concern:

Be it known that I, FREDERICK L. KINSEY, a citizen of the United States, and resident of Buffalo, in the county of Erie and State 5 of New York, have invented certain new and useful Improvements in Locking Hat, Coat, and Umbrella Racks, of which the following is a specification.

This invention relates to an improved coat 10 and hat rack provided with means for locking coats, hats, and umbrellas thereto so that only the parties in possession of keys can remove them from the racks.

My invention has for its objects the production of a rack of this character which is 15 not only ornamental, but thoroughly practical as an article of utility.

Another object of my invention is the provision of a hat and coat rack of simple 20 and durable construction whereby coats of different thicknesses of material or a number of coats can be securely locked upon the coat-hook; also in which the locking mechanism coöperating with the hat-hook accommodates itself to the thickness of the material of the hat.

Another object of my invention is to so construct the rack that a locking-lever co-operating with the coat-hook need only be 25 operated to lock a coat, hat, and umbrella thereto, and wherein provision is made to automatically release the locking elements upon inserting a key and turning the same.

A still further object of my invention is 30 to so combine a lock with a hat, coat, and umbrella locking-mechanism of the rack, that only after said locking-mechanism is moved into locking position can the key be removed from the rack; and upon insertion 35 of the key into the rack and turning the same to coöperate the slide bolt of the lock, can the locking-mechanism be released.

Still further objects are to provide a yielding or compensating connection between 40 the coat locking-element and the hat locking-element, so that both will effectively lock articles placed upon their coöperating hooks even though the article supported on one hook is considerably thicker than that 45 supported on the other; to provide means to lock the coat locking-element at various points in its movement; and to otherwise improve on devices of this kind.

With the above objects in view, my invention 50 consists in the combination and ar-

angement of devices and also in the construction, arrangement, and combination of parts to be hereinafter described and particularly set forth in the subjoined claims.

In the drawings forming part of this 60 specification and consisting of three sheets,— Figure 1 is a side elevation of a rack constructed according to my invention, the locking elements being shown in their normal or unlocked position. Fig. 2 is a front 65 elevation of the same. Fig. 3 is a side elevation showing a hat and umbrella, and a coat in dotted lines upon their respective supporting-hooks and the locking-elements coöperating with said hooks in locked position. Fig. 4 is a rear view of the same with the facing or closure-plate removed. Fig. 5 is a central vertical section taken on line 5—5, Fig. 2. Fig. 6 is a horizontal section taken on line 6—6, Fig. 1. Fig. 7 is a horizontal section taken on line 7—7, Fig. 1. Fig. 8 is a detached perspective view of the vertically movable actuating-rod whereby the locking-element for locking an umbrella to the rack is actuated. Fig. 9 is a perspective view viewed from the rear of the casting, the hat hook and the operating-lever on the reverse side being omitted.

Having reference now to the drawings in detail, like letters of reference refer to like 85 parts in the several figures.

The reference letter A designates the support or body of the rack which is preferably an elongated rectangular piece of wood capable of being fastened to a wall, screws a 90 being shown for that purpose, the edge of the support or body being rounded or otherwise fashioned to give the rack a neat appearance. Said support or body is provided with an elongated depression B on its rear side to provide a chamber for the reception of the operating mechanism; said chamber being provided with openings b, b¹, b², extending through to the front of the support or body, through which openings the several locking-elements extend, as will appear hereinafter. Said chamber B is closed at the rear by a plate C which faces the entire rear surface of the support or body and is fastened thereto by means of screws c or in any other suitable manner; said plate when secured in place, forming part of said support or body.

At one side of the depression or chamber 105 an extension c¹ is provided, which faces out 110

ward and in which a key-actuated slide-bolt is situated for free movement. Closing the extension c^1 and the opening b^1 , is a casting D which is applied to the front of the support A by means of screws d or otherwise. Formed integrally with said casting is a coat-hook or support D¹ and a hat-hook D² preferably curved outward and upward from a point near the upper end of said casting and terminating in an enlargement or head d^2 having its upper face convex. These hooks or supports may be of any desired shape so long as they are capable of serving the purpose intended therefor. At the junction of the casting D with the hat hook D² is a lug d^1 . A slot or opening d^3 extends through the casting D at this point so as to pass entirely through said lug, and said opening registers with the opening b^1 in the support A. Extending through said slot or opening d^3 and pivotally secured therein, is a lock-lever E having its rear end terminating in the depression or chamber B and its front end extending out beyond the lug d^1 a considerable distance. At its front end, said lock-lever has a depending portion e terminating in an enlargement e^1 whose lower face is concaved, as at e^2 for coöperation with a convex portion d^4 formed on the coat-hook D¹.

When a coat is hung upon the coat-hook in the manner shown in dotted lines in Fig. 3, and the lock-lever E is swung downward for coöperation with said coat-hook, the concaved portion e^2 of said lock-lever will impinge against the coat and lock the same on the coat-hook without wrinkling it. The front end of the lock-lever E is beveled, as at e^3 , and it has a slot e^4 in which is pivoted a handle F; said handle being provided with a narrow rear end portion f adapted to fit into said slot and having obliquely disposed shoulders f^1 adapted to bear against the beveled front edge of the lever E for the purpose of limiting the downward movement of the handle. The lock-lever E is therefore the means provided for operating the device.

On the rear face of the casting D is a fixed vertical series of teeth G adapted to be engaged by a pawl or dog G¹ having its upper end pivotally connected to the lock-lever E which is bifurcated at its inner end, as at e^5 . Said pawl is disposed vertically within the chamber B and has its lower end curved toward the series of teeth G so that when the lock-lever E is depressed, said pawl will engage one of the teeth of said series and hold said lock-lever in depressed position. Coöoperating with the pawl or dog G¹, is a slide or lock-bolt H having a beveled portion at one end, as at h, which is designed to engage the rear edge or face of said lock-pawl and swing the same outward to cause it to become disengaged from the se-

ries of teeth G. Said slide or lock-bolt moves horizontally while the pawl or dog G¹ moves vertically, and engaging said bolt, is a spring h¹ adapted to move the same in one direction and to retain the same in its normal position. Said slide or lock-bolt is movable between two guides h² arranged horizontally on the rear face of the casting D, and for the purpose of retaining said bolt between said guides, each guide has a lip h³ formed thereon which bears against the face of said bolt. A key retaining-lever h⁴ is pivoted to the rear of said casting and at its free end it has a depending portion h⁵ which is adapted to enter between prongs h⁶ on a key h⁷ inserted through a key-hole h⁸ formed in said casting; said key retaining-lever having a slot h⁹ at its free end through which is passed a screw h¹⁰ that takes into the casting D. With a view of holding said key-retaining lever elevated, a spring h¹¹ is provided which is secured to said lever and bears against the upper guide h². The key retaining-lever is positioned transversely on the casting D and when elevated, its upper edge is above the bottom of the slot or opening d^3 formed in said casting.

When the lock-lever E is in its elevated position, as shown in Figs. 1, 2, and 5, the inner end thereof bears against the upper edge of the transversely-disposed key retaining-lever h⁴, thus holding said last-mentioned lever in depressed position against the action of the spring h¹¹. This is the position of the parts when the lock-lever E is held out of coöperation with the coat-hook D¹, and at such times, the free end of the key retaining-lever is in engagement with the prongs h⁶ of the key and prevents removal of the key from the device. Upon depressing the lock-lever E, the inner end thereof is elevated and the key retaining-lever immediately follows the upward movement of said inner end, due to the action of the spring h¹¹ and immediately said key-retaining lever is forced upward sufficiently to clear the prongs of the key, the latter may be removed from the device. It is of course understood, that before depressing the lock-lever E, a coat has been placed upon the coat-hook D¹ so that when said lock-lever is depressed it will bear against said coat and prevent removal thereof from said hook.

When the lock-lever E is depressed, the key may be inserted into the key-hole h⁸ formed in the casting D, and upon turning the same, one of the prongs h⁶ of said key engages a shoulder H¹ formed on the slide or lock bolt H and forces said bolt laterally to move the beveled portion or wedge h in rear of the pawl or dog G¹, thereby disengaging said pawl or dog from the ratchet teeth G and permitting the lock-lever E to swing into its elevated position. For this

purpose a retractile spring I is provided within the chamber B which has one end secured to the wall of said chamber, as at *i*, and its other end secured to the inner end of 5 said lock-lever, as at *i*². Therefore, when the pawl or dog is disengaged from the teeth G, the spring I causes immediate and almost instant return of the lock-lever to its normal or elevated position.

10 To prevent theft of garments hung upon the rack by forcing the lock-lever E upward, the length of the handle F is such as to strike the hat-hook D² in any position the lever E may be in, when said lever is swung 15 upward. Therefore it will be impossible to obtain any purchase on the lever to force it out of locked position, and in order to check the jar and minimize the noise necessarily following a quick return of the lock-lever E,

20 a rubber buffer J surrounds the hat-hook D² and the handle F of the lock-lever is carried by momentum upward beyond the angle into which said lock-lever swings and comes in contact with said buffer, thus eliminating 25 the jar and noise which would otherwise occur. Some provision must be made to hold the pawl or dog against the ratchet teeth, and this I preferably do by means of a spring; but as I have combined other mechanism with the coat-locking lever, I find it of 30 advantage to secure a spring for this purpose on one of the parts of such other mechanism; but when constructing a rack having only a coat locking-device, the spring to hold 35 said pawl or dog inward against the teeth G or the casting D, may be secured in any suitable manner.

Near the upper end of the support A, I 40 secure a casting K having a slot or opening *k* registering with the opening *b* in said support. Passing through said slot or opening *k*, is a lock-lever K¹ having an enlargement or head *k*¹ at its outer end adapted to cooperate with the hat-hook D², said lever being 45 pivotally connected to said casting by means of a pivot-pin *k*² and its inner end is bifurcated to pivotally receive the upper end of a telescopic rod L having its lower end pivotally secured to the bifurcated inner 50 end of the lock-lever E, as at *l*.

The rod L comprises a solid member L¹ and a tubular member L² adapted to receive said solid member, and within said tubular member is a rubber or other yielding element *l*¹ against which the lower or inner end 55 of member L¹ bears. For the purpose of retaining said lock-lever K¹ in normal or elevated position and also for the purpose of holding the lower or inner end of member L¹ against the yielding element *l*¹, a retractile spring M is provided which is situated 60 in the chamber B and has one end secured to a pin *l*² projecting laterally from the member L¹ of said rod and its other end fastened to the wall of said chamber, as at *l*³.

The rod L therefore provides a yielding connection between the lock-levers E and K¹ so that the lever E can be continued in its downward movement after the lever K¹ cooperates with the hat-hook D² to lock a hat 70 thereon. This permits coats of different thicknesses or a number of coats to be hung upon the coat hook D¹, yet so actuates the lock-levers that both the coat or coats and the hat will be securely locked to the rack. 75

Although in the drawings the space between one end of the lock-lever K¹ and its coöperating hat-hook is greater than the space between the concaved portion *e*² of the lock-lever E and the coat-hook D¹, the end of 80 the lock-lever K¹ will contact with the convex head of the hat-hook D² before the concaved portion *e*² of the lever E cooperates with the hat-hook D² on account of the difference in leverage provided in the 85 connection of the rod L to said lock-levers. After the lock-lever K¹ is depressed to lock a hat, there may be a slight additional movement of the lock-lever E required to bring it in contact with a coat placed upon the 90 coat-hook D¹ and this additional movement of the lever E is permitted by the element *l*¹ yielding or being depressed within the member L² of the rod L. The lock-lever E after being depressed will be locked against 95 return movement by the dog or pawl G¹ engaging one of the series of teeth G and therefore, regardless of the thickness of the coat, or the number of coats placed upon the coat-hook D¹, said lock-lever will effectively lock 100 a coat or coats to said hook. I also provide means for locking an umbrella to the rack, and for this purpose a casting N is secured to the support A near its lower end, said casting having an opening *n* registering with the opening *b*² in said support and having 105 also a rigid laterally-curved supporting-hook *n*¹. Coöperating with said supporting-hook, is an oppositely curved lock-hook or lever N¹ pivotally secured to the casting N, as at *n*², and having an arm *n*³ passing through the openings *n* and *b*² and extending into the chamber B. The lock-lever N¹ is held in normal or unlocked position by 110 means of a spring O secured to the side wall of the chamber B and passing around a screw *o* threaded into the end of the arm *n*³, said spring being preferably a coil-spring passed around said screw and having both ends secured to a common point on the support A. While the spring herein shown serves the purpose intended to good advantage, any other spring or equivalent means may be substituted to retain the lock-lever or lock-hook N¹ in normal or unlocked position so that an umbrella can be placed between the ends of said hook or lever and the hook *n*¹.

P designates an actuating rod arranged vertically within the chamber B and hav-

120

125

130

ing its upper end secured to the inner end of the lock-lever E, as at p, and its lower end guided for vertical movement in a guide-opening p^1 formed in the support A, said 5 actuating-rod having a lateral extension p^2 provided with an inclined contact-face p^3 adapted to co-act with the inner end of the arm n^3 formed on the lock-hook or lever N^1 . Although the spring I may be sufficient to 10 assure proper actuation of the actuating-rod P, I have also provided a retractile spring Q which is located within the chamber B and has one end secured to the point of pivotal connection of said rod to the lever E, as at q, and its other end to the wall of the chamber B, as at q^1 .

By placing the springs I and Q on opposite sides of the lock-lever E, which in reality is the operating-lever of the device, an 20 even movement is obtained for the several working parts so that friction is reduced to the minimum. The lateral extension p^2 is so positioned with relation to the lock-hook or lever N^1 that when the operating- 25 lever E is in elevated or normal position, said lateral extension is in a plane beneath the lock-hook or lever N^1 , and not until lever E is being depressed will the beveled surface p^3 of said extension act against the arm n^3 of said lock-hook or lever. When, however, 30 said beveled surface engages said arm, the hook or lever N^1 is swung toward the rigid hook n^1 and securely locks an umbrella to the rack.

35 I preferably provide the actuating-rod P with a lateral stud R to which I secure a spring r adapted to press against the rear or outer edge of the pawl or dog G¹ to force and retain the actuating end of said pawl 40 or dog in engagement with the casting D beneath the vertical series of teeth G or with one of the teeth of said series. When the lock-lever E is in normal position, the actuating end of the pawl or dog is held in engagement with the casting D beneath the 45 series of teeth G, as shown in Fig. 5.

The operation of the device is as follows,— Normally the parts are in the position shown in Figs. 1, 2, and 5, with the key h^7 retained in the key-hole by the key retaining-lever h^4 . When it is desired to lock a coat, an umbrella, or a hat, or any two or all of said articles to the rack, they are hung upon the proper supporting-hooks provided therefor and the operating-lever E depressed until the concaved portion e^2 of the latter comes in contact with the coat on the hook D¹, or if no coat is placed on said hook, until said lever contacts with said hook or reaches the 55 end of its downward movement, as the case may be. This downward movement of the operating-lever causes its inner end to swing upward thereby forcing the actuating-rod L upward to impart motion to the lock-lever 60 65 K¹ and swing the same toward the upper end

of the hat-hook, as shown in Fig. 3, and drawing the actuating-rod P upward to cause the beveled surface of the extension p^2 , which may well be termed a cam, to engage the inner end of the lock-hook or lever N^1 and force the same toward the rigid hook n^1 . Any articles that may be hung upon the respective hooks will therefore be locked in place.

When the several locking elements are 75 locked and positioned as described, the inner end of the operating-lever will be elevated and permit the key retaining-lever to assume its released position, in which position it is out of engagement with the prongs 80 h^6 of the key and permits said key to be withdrawn so that it may be carried away by the person having locked his property to the rack, thus preventing the removal of the same except by the owner or a person to 85 whom he may deliver the key.

When the article or articles are to be removed from the rack, it is simply necessary in order to release them, to insert the key and turn the same within the key-hole, 90 whereupon the prongs or one of the prongs h^6 of the key will engage the shoulder H^1 of the slide or lock-bolt H and force the same laterally against the action of the spring h^1 . This movement of the slide or 95 lock-bolt will bring the beveled portion or wedge h thereof in contact with the front or inner edge of the pawl or dog G¹ and force the same rearward against the action of the spring r bearing thereagainst, thus disengaging said pawl or dog from the tooth of the series G co-acting therewith; and immediately the pawl is disengaged, the springs I and Q act to swing the operating-lever E into normal position, or in other words, the 105 inner end of said operating-lever is swung downward, causing the pawl or dog G¹ to move downward out of contact with the series of teeth. The actuating-rod P is also moved downward to engage the cam p^2 110 thereof from the lock-hook or lever N^1 , whereupon the spring Q moves said hook or lever away from the rigid hook n^1 . During such action of the operating-lever the actuating-rod L is drawn downward and 115 causes the lock-lever K¹ to swing upward, thus permitting any article that may be hung upon the several hooks to be removed. The downward movement of the inner end of the operating-lever E causes the key-retaining lever h^4 to be moved downward to bring its outer end in engagement with the key between its prongs h^6 , thereby locking said key against removal, and not until after 120 the several locking-elements are moved into locking position can the key again be removed.

Having thus described my invention, what I claim is,—

1. A device of the character described,

comprising a support having a chamber and an opening extending from said chamber to the outer face of said support, a casting secured to said support and closing said opening, said casting having a projection on its outer face on which an article may be hung and a vertical series of teeth on its inner face, a lever pivotally attached at a point between its ends to said casting and adapted to coöperate with said projection, a spring-pressed pawl pivotally attached to the inner end of said lever and adapted for co-action in said vertical series of teeth, and means to disengage said pawl from said teeth.

15 2. A device of the character described, comprising a chambered support having an opening extending from its chamber to the outer surface of the support, a casting applied to the outer face of said support and closing said opening, said casting having an opening registering with the above-mentioned opening and a hook extending upward therefrom, also a vertical series of teeth on its rear face, a lock-lever extending through the opening in said casting and pivoted at a point between its ends within said opening, a pawl pivoted to the inner end of said lock-lever and adapted for co-action with said vertical series of teeth, a horizontally-disposed slide-bolt having a wedge-portion adapted to engage said pawl to free it from said teeth, a removable key adapted to actuate said slide-bolt, and a spring-lifted key retaining-lever adapted to engage said key to prevent removal thereof, said key retaining-lever being engaged by the inner end of said lock-lever when in normal position.

30 3. In a device of the character described,

in combination, a hat locking-device including a swinging lever, means for locking said lever, a hat locking-device including a swinging lever, a rod connecting said levers and comprising two yieldingly connected members, and means for releasing said first-mentioned lever when locked.

4. In a device of the character described, the combination with a support having a coat-hook and a hat-hook, of a lever co-operating with each of said hooks, a telescopic rod connecting said levers, means for locking the lever coöperating with said coat-hook, and means for releasing said lever when locked.

5. In a device of the character described, the combination with a support having a coat hook and a hat hook thereon, of a lock-lever coöperating with each of said supports and pivoted between its ends, a rod connecting corresponding ends of said levers and comprising two members, one of said members being tubular and having a yielding element located therein and the other member fitting within said tubular member against said yielding element, means for retaining said lock-levers in unlocked position, means for locking said levers when actuated, and key-actuated mechanism for releasing said levers so as to permit them to return to normal position.

In testimony whereof, I have affixed my signature in the presence of two subscribing witnesses.

FREDERICK L. KINSEY.
